WILLIAM PARKIN, OF TAUNTON, MASSACHUSETTS, ASSIGNOR TO
REED AND BARTON, OF SAME PLACE.

Design No. 3,421, dated March 23, 1869.

DESIGN FOR A BOTTLE-STAND, OR CASTER.

The Schedule referred to in these Letters Patent and making part of the same.

To all persons to whom these presents may come:

Be it known that I, WILLIAM PARKIN, of Taunton, of the county of Bristol, and State of Massachusetts, have invented, or produced a new ornamental Design for a Caster, or Bottle-Stand; and do hereby declare the same to be fully described in the following specification, and represented in the accompanying drawing, which denotes a side elevation of it.

In such drawing—

The base, A, of the caster, is shown as a flat conic frustum, formed with three offsets, *a b c*.

Extending above this is a column, B, over which is a rotary bottle-stand, or carrier, C.

It has a milled band, *d*, around it, near its base, below which project six balls, *e e e e e e*.

There is to the carrier C, a bell-shaped neck, *f*, above which rises the handle, D, which is formed in manner as represented, its upper part having, on its flank, two female heads, or busts, *g g*.

I claim the ornamental design for a caster, as above described, and as represented in the accompanying drawing.

WILLIAM PARKIN.

Witnesses:

O. P. HARRIS,
W. W. SWAN.
